JAMES TROUP HORNE, OF ROCK FERRY, ENGLAND.

SHIP CONSTRUCTION.

1,114,263.

Specification of Letters Patent. Patented Oct. 20, 1914.

Application filed March 15, 1913. Serial No. 754,490.

To all whom it may concern:

Be it known that I, JAMES TROUP HORNE, a subject of the King of England, residing at 43 Highfield south, Rock Ferry, in the county of Chester, England, have invented a new and useful Improved Ship Construction, of which the following is a specification.

This invention has reference to the construction of parts of the internal structure of ships, and means for obtaining access to and egress from the "tween decks" and holds of same; and the structure according to it is such, that it serves as a part of the means for supporting the decks from the tank top or bottom of the ship, namely, as a pillar used between the decks, and as means for gaining access to and egress from the spaces or chambers between the different decks, or some of them, and the lower holds; and other uses hereinafter described. These combined pillars and access and egress means are preferably made of steel or iron plates of relatively large size, and of rectangular, cylindrical, triangular or other suitable form; so that a man can pass up and down within them; and they are provided or fitted with rungs or ladder parts, so that men can climb up them from one deck to another, and from the bottom of the ship to the top; and from all of them, to the upper deck of all. And they are built into the decks, or floor and decks, so that they serve as some of the pillars of the ship's structure, in addition to their being a means of access and egress, and occupy the space in the interior of the hold, of the ordinary pillars, which would ordinarily not be available for use. By this invention, therefore, little or no material space is taken off the available 'tween-deck and hold capacity for the storage of cargo, and so no loss of cargo space is occasioned by the application of the invention, nor diminution of structural strength. In some cases, one, two or more sides or parts of this "ladder-pillar" is or are open for purposes hereinafter described; and in some cases the ladder rungs are fixed in the interior of pillar, for the whole or part of its length, or form portions of it; while in other cases the rungs or ladder lengths are movable or portable, and fitted in it.

The invention is illustrated in the accompanying drawings, in which—

Figure 1 is an elevation showing one ap-

plication of the invention to a ship, and Fig. 2 is an elevation viewed at 90 degrees from the view represented in Fig. 1; and Fig. 3 is a cross-section in plan. Fig. 4 60 is a plan of a portion of a ship illustrating the application of the invention.

Referring to the drawings, Fig. 4 illustrates in plan, a ship's hold extending between the two bulk-heads *a*, and showing 65 a hatch-way *y* in the deck, and pillars *z*, extending vertically through the ship and rendering support to the deck structure near and about the hatchway; the arrangement of pillars shown being that commonly employed; that is, the pillars stand some short distance away from the hatchway openings *y*, and at each corner of same, and lend support to the girder or part of the structure extending along the sides of the hatchway, and so to the beams which extend between them and the side of the ship. 70

Referring now to the drawings, and more particularly to Figs. 1, 2, and 3, *a* is the tank top at the bottom of the ship; *b* represents the main deck of the ship; and *c* the upper deck; *d* represents the girders and coamings around the hatchways in the decks *c* and *b*; and *e* are the deck beams extending between the side girders *d* of the hatchway 85 *y*, and the sides of the ship. The pillars extending between the bottom *a* and decks *b* and *c* are generally designated *z*; and they are disposed in the usual positions above described in relation to the longitudinal 90 girders forming part of the sides of the hatchway *y*, and to the deck beams *e*. The pillar or pillars according to this invention, may be any one (or more) that may be most convenient; and it may be assumed that one 95 of the four shown in the plan in Fig. 4 is according to the invention. At the lower end, the ladder-pillar *z*, is built into the tank top *a* of the ship; and in this tank top, a manhole *a*¹ is provided, and is normally 100 firmly closed by a manhole cover; but by removing the cover, access is had to the interior of the tanks or bottom of the ship *a*, for gaining access to it for passing a hose or pipe down into it, by way of the pillar 105 *z* or other purpose. The top of this lower portion of the ladder-pillar is built into the plate *f* connected with the bottom of the hatchway girder *d*; this plate being carried toward the side of the ship some distance 110 as shown, and connected also with two of the deck beams *e* by the plate structure *g*,

in the well known way. The plate *f* has an opening *f*¹ in it for passing up and down, which coincides vertically with the top of the pillar *z*.

5 The bottom of the ladder-pillar extending between the main deck *b* and the upper deck *c*, is built into the deck *b*; and is provided with an opening *b*¹ directly under the pillar; while the upper end of this pillar is secured 10 to the plate *h* secured to the girder *d* of the hatchway and the beams *e* by the plate structure *g*, similarly to the plate *f* in the lower structure just described; *h*¹ being an opening in it. Above this pillar and an opening 15 *c*¹ in the upper deck *c*, there is a tubular structure *i*, serving as a ventilator coaming; and through this tube or coaming *i*, access is had to the ladder-pillar below; and this access can be had at all times, to the pillar 20 from top to bottom; and thereby to the 'tween-deck, or 'tween-decks, lower hold, and to the ballast tanks. The tube or coaming *i* may, instead of serving for a ventilator base, serve the purpose of a "samson post", 25 or if desired it may be extended up to form a platform or base for a derrick. When fitted with a removable ventilator cowl, the pillar and cowl themselves are adapted to 30 serve as a ventilating means to the holds or spaces below.

The ladder portions within the pillars *z* are marked *l*, and their position is preferably that shown in the drawings. They may be of any suitable construction, with 35 side bars, and rungs of metal, such as are commonly used in ships. The pillars *z*, in the case shown, are rectangular in form, and they are made of plating on three sides, which close these sides; while at the fourth 40 side there are open parts; and the two in-turned corner portions of the plating referred to, are connected together by straps or plates *k*. The side, as the drawing shows, is away from the opening of the hatchway, 45 and toward the sides of the ship or bulkheads. One of these plates *k* is always fitted and used at the bottom of the lengths of pillars, where they are built into the deck, so as to form a coaming or closure to the 50 pillars at the lower parts. Also, a plate *k* is used at the top of the pillars, while between these, intermediate strap plates *k* are arranged at intervals, as shown. Through the 55 openings between these straps or die bars *k*, a man can pass into or out of the cargo space in the various parts of the ship.

As shown in Fig. 3, the interior of the ladder pillar at one or more parts or sections, is provided with internal channels *m* or the like adapted to receive and have fitted 60 in them boards, plates or the like for closing the opening or openings of the pillars; so that when the vessel is carrying in its hold or space, cereals, coal, ore, or other cargo in bulk, it is prevented from getting into the 65 interior of the pillars. In the case where the tube or coaming *i* forms a derrick platform or box, or a "samson post", one or more 70 openings may be formed in its side or sides, for the purpose of gaining ingress into, and egress from the holds, chambers, or spaces 75 below; and it may have grips or rungs on its inside for enabling the users to climb up and down in it; or, if desired, the entrance to the tube, may be solely through the upper 80 open top of this coaming or tube *i*. The outside of the pillars may be fitted or provided with battens or guards of any suitable material, to prevent cargo being chafed or damaged if it should come into contact 85 with the material forming the pillar; and the interior of the pillar can be fitted with pipes to serve as air pipes, sounding pipes, steam injecting pipes fire indicator pipes or for other purposes. In the case shown, the 90 pillar is made largely of metal plates or plating; but in others it may be made of a plurality of vertical stanchions or bars of "section metal."

What is claimed is:—

In a ship, the combination of hatchways, 90 decks with apertures in proximity to the hatchways, deck beams attached thereto, plate structures connected with the deck beams, plates with apertures attached to 95 the structures with the apertures disposed beneath the apertures in the decks, hollow supporting pillars disposed in line with the said apertures and attached to the said 100 decks and plates, ladders disposed within the hollow pillars for enabling a person to pass up and down the pillars and through the said apertures, and means for entering and passing out of the hollow pillars.

In testimony whereof I have signed my 105 name to this specification in the presence of two subscribing witnesses.

JAMES TROUP HORNE.
